Primary Examiner — Samantha Q Lawrence

(57) CLAIM

The ornamental design for babies' napkin cover, as shown and described.

DESCRIPTION

1. Babies' napkin cover

The broken lines shown in Figures 1.1 and 1.2 illustrate portions of the babies napkin cover that form no part of the claimed design.

1 Claim, 5 Drawing Sheets(56)
